US00D469254S

(12) **United States Design Patent** (10) Patent No.: **US D469,254 S**
Johnson (45) Date of Patent: ** Jan. 28, 2003

(54) **TRANSPORT CASE FOR PORTABLE EXPANDING FILE FOLDERS**

(75) Inventor: **Lynne B. Johnson**, St. Louis County, MO (US)

(73) Assignee: **Cardinal Brands, Inc.**, St. Louis, MO (US)

(*) Notice: This patent is subject to a terminal disclaimer.

(**) Term: **14 Years**

(21) Appl. No.: **29/155,529**

(22) Filed: **Feb. 11, 2002**

Related U.S. Application Data

(63) Continuation of application No. 10/054,198, filed on Jan. 22, 2002, which is a continuation of application No. 09/921,974, filed on Aug. 3, 2001, now Pat. No. 6,364,110.

(60) Provisional application No. 60/222,571, filed on Aug. 3, 2000.

(51) **LOC (7) Cl. 03-01**

(52) **U.S. Cl. D3/303; D3/900; D3/902**

(58) **Field of Search** D3/232, 233, 303, D3/900, 902; D19/26, 75, 78, 86, 92; 150/100, 149, 900; 190/11, 109, 111-114, 119, 900-903; 206/311, 425; 229/67.3, 67.4

(57) **CLAIM**

The ornamental design of a transport case for portable expanding file folders, as shown and described.

DESCRIPTION

FIG. 1 provides a perspective view of the design when in a closed position.

FIG. 2 provides a front cover elevational view of the design.

FIG. 3 provides a rear cover elevational view of the design.

FIG. 4 provides a top edge plan view of the design in a closed position.

FIG. 5 provides a spine (bottom) edge plan view of the design.

FIG. 6 provides a left side edge plan view of the design in a closed position.

FIG. 7 provides a right side edge plan view of the design in a closed position; and,

FIG. 8 provides a perspective view of the design when in an open position. The broken lines define a file folder of the type which can be placed within the design and form no part of the claimed design.

1 Claim, 6 Drawing Sheets
